United States Patent [19]

Krichever et al.

[11] Patent Number: Des. 305,884

[45] Date of Patent: ** Feb. 6, 1990

[54] **HAND-HELD LASER SCANNING TERMINAL**

[75] Inventors: **Mark Krichever, Hauppauge; Boris Metlitsky, Stony Brook, both of N.Y.**

[73] Assignee: **Symbol Technologies, Inc., Bohemia, N.Y.**

[**] Term: **14 Years**

[21] Appl. No.: **281,686**

[22] Filed: **Dec. 9, 1988**

[52] U.S. Cl. **D14/116; D18/7**

[57] CLAIM

The ornamental design for a hand-held laser scanning terminal, as shown and described.

DESCRIPTION

FIG. 1 is a top, front, right side perspective view of a hand-held laser scanning terminal showing our new design;

FIG. 2 is a top plan view thereof on an enlarged scale; FIG. 3 is a front elevational view thereof on an enlarged scale;

FIG. 4 is a left side elevational view thereof on an enlarged scale;

FIG. 5 is a right side elevational view thereof on an enlarged scale;

FIG. 6 is a rear elevational view thereof on an enlarged scale;

FIG. 7 is a bottom plan view thereof on an enlarged scale.

FIG. 1

FIG. 2

FIG. 3

FIG. 4

FIG. 5

FIG. 6

FIG. 7
